UNITED STATES PATENT OFFICE

STUART W. PARSONS, OF NEW BRITAIN, CONNECTICUT, ASSIGNOR TO THE STANLEY WORKS, OF NEW BRITAIN, CONNECTICUT, A CORPORATION OF CONNECTICUT

FRICITION BUTT

Application filed June 18, 1927. Serial No. 199,818.

The present invention relates to a hinge or butt having means for frictionally holding the door or other swinging member hung on the hinge in any desired position, and for preventing the door from swinging too rapidly into closed or open position. My improved hinge may be employed wherever it is desirable to hold a swinging member frictionally in any desired position and where it is desirable to prevent slamming of the hinged member, and finds particular use for doors of hospitals, hotels and the like.

The aim of the invention is to provide an improved hinge of this sort which is very simple in construction and reliable and effective in operation.

A further aim of the invention is to provide a friction butt wherein the weight of the swinging member is borne entirely by the butt, the frictional device bearing none of this weight.

A still further object of the invention is to provide a butt with a frictional device having relatively large frictional surfaces or areas so that wear of the frictional members is reduced to a minimum, and the friction between these members can be adjusted with great nicety.

A still further aim of the invention is to provide a frictional device, the parts of which form an assembled unit, the frictional elements of which may be readily renewed when necessary, the frictional unit being easily assembled on and disassembled from the leaves of the butt.

Other objects will be in part obvious and in part pointed out more in detail hereinafter.

The invention accordingly consists in the features of construction, combination of elements and arrangement of parts which will be exemplified in the construction hereinafter set forth, and the scope of the application of which will be indicated in the appended claims.

In the accompanying drawings, wherein I have shown one of the embodiments which the present invention may take:

Figure 1 is a front view of the butt with

a portion of the upper knuckle broken away for purpose of illustration;

Fig. 2 is a vertical sectional view taken substantially on line 2—2 of Fig. 1;

Fig. 3 is a horizontal sectional view taken substantially on line 3—3 of Fig. 1;

Fig. 4 is also a horizontal sectional view taken substantially on line 4—4 of Fig. 1; and

Fig. 5 is a perspective view of the parts of the frictional unit.

Referring to the drawings in detail, A and B respectively designate the leaves of the butt or hinge. The leaf A has between its ends a pair of knuckles 10 and 11 between which is a space in which the friction unit, designated generally by the letter C, is positioned. The leaf B has a pair of end knuckles 12 and 13, the former of which is positioned above the knuckle 10, and the latter of which is below the knuckle 11; that is to say, the knuckles 12 and 13 straddle the knuckles 10 and 11. If desired, there may be interposed between the knuckles of the two leaves ball bearing units 14. These units may be secured to the knuckles 12 and 13 by tubes or eyelets 15.

The letter D designates the pin or pintle for connecting the leaves together, and this pintle, as hereinafter described more in detail, is employed for adjusting the friction device. In the present illustrative disclosure, the pin is shown as having a portion 16 of larger diameter adapted to engage in the knuckles 12 and 10 and a portion of smaller diameter 17 adapted to engage in the friction device and the knuckles 11 and 13, there being a shoulder 18 between the portions 16 and 17 which is adapted to engage on the friction device. Adjustably connected, as by means of a set screw 19 to the upper end of the pin, is a cap or tip 20 which gives a finished appearance to the hinge. The inner end of the screw 19 is adapted to engage in a vertical groove 21 in order to prevent rotation of the cap relative to the pin and to permit of longitudinal adjustment of the pin relative to the cap. The pin, adjacent its upper end, has a pair of lugs 22 adapted to engage in notches 23 in the opening through the upper

knuckle 12 so that the pin is held against rotation with respect to the leaf B. The lower end of the pin D which extends beneath the lower knuckle 13 is threaded so as to receive a nut 24 by means of which the pin may be drawn down against the friction device. This nut is counterbored, as at 25, so as to receive a split spring washer 26. The pin may have an oil groove or passage 27 leading from the top of the pin to the shoulder 18.

In the present illustrative disclosure, my improved friction device comprises a plurality of superimposed friction elements in the form of disks or washers, alternate disks 35 being connected to the leaf A and intervening ones 36 to the leaf B so that, when either of these leaves is swung with respect to the other one, each disk will move with respect to the next adjacent one. For causing the disks to rotate with the respective leaves, each disk has a pair of lugs 37 with a notch therebetween. The notches are of substantially the same width as the gauge of the leaves in order to closely receive the edges of the leaves. By preference, the disks are made alternately of steel and brass, in the present instance the disks 35 being of brass and the disks 36 of steel in order to obtain a good frictional bearing between the members. The body portions of the disks or washers are substantially round so as to conform to the knuckles and thus give a unity of design to the hinge. In order to facilitate assembly of the friction device upon the hinge leaves, the friction members are connected to form a unit, in the present instance this being accomplished by a sleeve or bushing 38 having, at its upper end, a flange 39 adapted to engage in a counterbore 40 in the uppermost friction disk. The sleeve is adapted to extend through the disks or washers, and its lower end is crimped or peened, as at 41. The lowermost friction disk is counterbored so as to receive the crimped edge of the bushing, as shown in Fig. 2. Also, the bushing has a plurality of holes 42 in order to permit lubricant to pass through the bushing to the friction disks. In order to make it easier for the carpenter or other person hanging the door, and to permit the hinge to be readily taken apart and again correctly assembled, the unit is connected to one of the hinge leaves. For example, the hinge leaf A may have a longitudinal score or groove 45 parallel to and adjacent the edge 46 which is received by the prongs of the friction disks 35, and one prong of each of these disks is bent or depressed into this groove, as shown most clearly in Fig. 3.

From the foregoing description, taken in connection with the accompanying drawings, it will be clear that the friction disks are held together as a unit by the sleeve 38. This unit may be assembled on the leaf A and held

against ready detachment from that leaf by depressing the prongs into the score or groove 45. Owing to this arrangement, the hanging of the door is facilitated. After the door is hung on the hinges, friction between the disks may be very easily adjusted by turning the nut 24. In the event that a greater amount of friction is desired so as to resist the swinging movement of the door, the nut may be turned up on the pin 16 to cause the shoulder 18 to bear more heavily upon the unit. In the event that it is desirable to have the door swing more freely, the friction may be relieved to the desired extent by loosening the nut 24.

As many changes could be made in the above construction and many apparently widely different embodiments of this invention could be made without departing from the scope thereof, it is intended that all matter contained in the above description or shown in the accompanying drawing shall be interpreted as illustrative and not in a limiting sense.

It is also to be understood that the language used in the following claims is intended to cover all of the generic and specific features of the invention herein described and all statements of the scope of the invention which, as a matter of language, might be said to fall therebetween.

What I claim as my invention is:

1. In a hinge of the character described, a pair of hinge leaves provided with aligned knuckles, friction means interposed between a pair of said knuckles and comprising superposed friction disks, said friction means being entirely outside of said knuckles, said disks being alternately connected to the respective leaves, a pin extending through said knuckles and disks and having a shoulder adjacent the lower end of the knuckle immediately above said unit, said shoulder being adapted to bear upon said disks, and means for adjusting said pin longitudinally to vary the pressure of said shoulder on said disks.

2. In a hinge of the character described, a leaf having a pair of rigid knuckles with a space therebetween, a second leaf having a pair of knuckles straddling said first mentioned knuckles, friction disks positioned in and substantially filling the space between said first pair of knuckles and alternately connected to the respective leaves, a pin slidably mounted in said knuckles and having a shoulder bearing upon said disks, and a nut for adjusting said pin longitudinally to thereby adjust the frictional engagement between said disks.

3. In a hinge of the character described, a pair of hinged leaves having aligned knuckles, a friction unit between the ends of said leaves and interposed between two of said knuckles, a pin slidably mounted in said knuckles and extending through said

- unit, means for holding said pin from rotation relative to one of said leaves, said pin having a shoulder adapted to bear upon said unit, a nut for longitudinally adjusting said pin, and a spring against which said nut bears.
4. In a hinge of the character described, a pair of leaves provided with aligned knuckles, a friction unit comprising a plurality of disks each having a pair of prongs with a notch therebetween, alternate disks having their notches receiving the edges of one leaf and intervening disks having their notches receiving the edge of the other leaf, means for securing the disks against ready detachment from one of said leaves, a pin extending through said knuckles and disks and adapted to bear upon said unit, and means for adjusting said pin to vary the friction of said unit.
5. In a hinge of the character described, a pair of leaves provided with aligned knuckles, a friction unit interposed between a pair of said knuckles and comprising a plurality of disks each having a pair of projections with a notch therebetween, the notches of alternate disks being arranged to receive the edge of one of said leaves and the notches of the intervening disks being arranged to receive the edge of the other leaf, one of said leaves having a groove or score and a prong of each disk associated with said leaf being depressed into said groove, a pin extending through said knuckles and unit and having a shoulder adapted to bear upon the unit, and means for adjusting the pin.
6. A hinge of the character described, a pair of leaves provided with aligned knuckles; a friction unit comprising superimposed friction disks alternately connected to the respective leaves and a sleeve extending through and holding said disks together; a pin extending through said knuckles and unit and adapted to bear upon said unit, and means for adjusting said pin to vary the friction between said disks.
7. In a hinge of the character described, a pair of leaves provided with aligned knuckles; a friction unit interposed between a pair of said knuckles and comprising superimposed disks alternately connected to said leaves and a sleeve extending through said disks, the opposite ends of said sleeve being flanged to hold the disks together; a pin extending through said knuckles and said sleeve and having a shoulder adapted to bear upon said sleeve, and means for adjusting said pin to vary the friction between said disks.
8. In a hinge of the character described, a leaf having a pair of knuckles with a space therebetween, a second leaf having a pair of knuckles straddling said first mentioned knuckles; a friction unit positioned in the space between said first pair of knuckles and comprising superimposed disks alternately connected to said leaves, and a sleeve extend-
- ing through and connecting said disks; a pin extending through said knuckles and sleeve and having a shoulder bearing upon said sleeve, and a nut for adjusting said pin, said pin having an oil groove and said sleeve being 70 perforated.
9. In a hinge of the character described, a leaf having a pair of rigid knuckles with a space therebetween, a second leaf having a pair of knuckles straddling said first mentioned knuckles, friction disks positioned in and substantially filling the space between said first pair of knuckles and each having a pair of prongs with a notch therebetween, alternate disks having their notches receiving the edge of one leaf and intervening disks having their notches receiving the edge of the other leaf, a pin slidably mounted in said knuckles and having a shoulder bearing against said disks, and means for adjusting said pin to vary the pressure of said shoulder on said disks.
